PORTABLE LIGHT

Norman C. Bates, 68 Bayview Ave., Amityville, N.Y.

Filed Sept. 25, 1962, Ser. No. 71,851

Term of patent 14 years

(Cl. D48—24)

Fig. 1

Fig. 2

Fig. 3

Fig. 4

Fig. 5

FIGURE 1 is a front elevational view of a portable light, showing my new design;

FIGURE 2 is a side elevational view thereof;

FIGURE 3 is a rear elevational view thereof;

FIGURE 4 is a top plan view thereof; and

FIGURE 5 is a bottom plan view thereof.

I claim:

The ornamental design for a portable light, substantially as shown.
